COMBINED MEMO BOARD AND TOWEL RACK

Lowell W. Bodenbach, 1000 Brice Road, Rockville, Md.

Filed May 31, 1963, Ser. No. 75,133

Term of patent 7 years

(Cl. D25—1)

FIG. 1.

FIG. 2.

FIG. 3.

FIG. 4.

FIG. 5.

FIGURE 1 is a top perspective view from the front of a combined memo board and towel rack showing my new design;

A roll of towels is shown by broken lines in FIG. 4 for illustrative purposes only.

The dominant features of my design reside in those portions shown in full lines, and primarily in the specific towel holding members, one of which is pivoted, in combination with the memo board, all as shown.

I claim:

The ornamental design for a combined memo board and towel rack, substantially as shown and described.
